FLUID PRESSURE ACTUATED BLAST GUN

Filed Jan. 15, 1951

UNITED STATES PATENT OFFICE

2,650,615

FLUID PRESSURE ACTUATED BLAST GUN

John Edward Crossley Nesham, Rochester, England, assignor, by mesne assignments, to Airnesco Products Limited, Rochester, England, a company of Great Britain

Application January 15, 1951, Serial No. 206,014
In Great Britain January 25, 1950

6 Claims. (Cl. 137—640)

1

This invention relates to a portable fluid pressure actuated blast or jet gun commonly referred to as a percussion blower being used mainly for removing soot from boiler tubes but capable of cleaning purposes generally where a powerful blast is required.

The invention is concerned with that type of blower comprising a casing having a pressure chamber from which fluid pressure, e. g. air or steam, can be discharged in a rapid succession of blasts, by opening and closing a valve leading to a discharge orifice, the valve normally being maintained on its seat by spring bias but being opened by air or other fluid pressure actuated piston to release air from the chamber until the force of the spring is sufficient to overcome the pressure and close the valve, whereupon the same cycle of operations takes place with the result that the gun emits a series of air or other fluid pressure blasts at high speed and pressure.

In practice certain manufacturing difficulties have arisen in the construction of the gun which in the prior art comprises a casing formed in three parts, the intermediate part incorporating the cylinder for the actuating piston.

The seat for the discharge valve is formed on an end part of the casing and it will be appreciated, therefore, that in order to secure a good seat of the discharge valve carried by the piston, it is necessary for the several parts of the casing to be accurately machined. Moreover, should undue wear of the valve or valve seat take place, it is impossible to regrind the valve seat without upsetting the dimensions so that it is no longer possible for the valve to close against its seating unless shims are removed from between the several parts of the casing.

The main object of the present invention is to provide an improved design of gun wherein the outer casing is reduced to a two-part construction, thereby reducing the possibility of leakage of pressure from within the main pressure chamber and enabling manufacturing operations and cost to be reduced owing to the simplicity of construction of the operating parts and the method of assembly. A further object of the invention is to provide for and simplify any minor adjustments due to wear, such as is liable to take place between the discharge valve and its valve seat, which can be made simply by removal of the valve seat and regrinding in the ordinary manner.

According to the present invention in a fluid pressure actuated blast gun the outer casing is in two parts and includes a cylinder block having a

2

cylinder in which a piston actuating the discharge valve is mounted to reciprocate and a second block having a valve seating against which the discharge valve closes, both the cylinder block and valve block being detachably secured within the casing.

In the preferred construction the cylinder block is constructed in the form of a spider, the arms of which are machined to fit within the casing and provide a direct passage for the pressure fluid from the inlet to the discharge end of the casing. The control valve for controlling the admission of air from the pressure chamber within the casing to the piston cylinder may be housed in a duct formed in one of the spider arms.

The casing preferably consists of a cylinder closed at one end and provided at its other end with a detachable screw-on cover plate by means of which the cylinder block and valve block are secured in position against a shoulder formed in the interior of the cylinder.

The invention is illustrated in the accompanying drawings, in which:

25 Figure 1 is a sectional view of a blast gun constructed in accordance with a preferred embodiment of the invention.

Figure 2 is an end view showing the centre piece and chamber housing the actuating piston of the gun.

30 Referring to the drawings, A indicates the outer casing of the gun, in the interior of which is provided a fluid pressure chamber B with an inlet I for admission of fluid, e. g. air or steam, and provided with a discharge outlet O from which is emitted in rapid succession a series of blasts of air or gas as the case may be at high momentum, the rapid opening and closing of the discharge outlet O being controlled by a discharge valve indicated at V.

35 Opening and closing movements of the valve V are brought about by a piston P operating in a cylinder indicated at C, the piston P normally being urged to a position wherein the valve V is closed to prevent the escape of pressure from the main cylinder B by a spring S. Displacement of the piston P against the action of the spring S is by fluid pressure fed to cylinder C from the chamber B. Admission of the fluid from chamber B to the interior of chamber C is by means of an interior duct and a second valve D, termed the control valve, this valve D usually being hand controlled by means of a control member indicated generally at M.

40 In the blast gun of this invention the main casing A comprises a barrel portion 100 closed

at one end and provided at its other end with a detachable cap portion 101' so that in effect there is provided a two-part casing with the advantage that leakage losses, which are likely to occur where the casing 100 is built up of more than two parts can be reduced to a minimum.

Referring now to Figures 1 and 2, the barrel portion 100 is bored at the end opposite to the screw cap 101' to receive a tubular member 102 constituting the inlet nozzle I while the cover plate cap portion 101' has a central orifice 103 to receive a tubular extension 104 on a valve block 105. The block 105 is internally tapered and is provided with a valve seat 40'.

The chamber C within which the actuating piston P reciprocates, may as shown be cast in one with the block 106, the block 106 being in the form of a spider and having conveniently three arms 107-107' which are machined at their ends 108 to fit a counterbore 109 in the casing 100. The piston chamber C is closed at its open end by a screw plug 110 which provides a seat for the valve closing spring. At its other end chamber C has an axial drilling 111 which provides a guide for a piston rod 112 fast with the piston P and carrying the discharge valve V as hereinafter described.

Both the valve block 105 and piston guide block 106 are a machine fit within the counterbore 109 of the casing 100 and are so dimensioned as regards their total axial depth that when the screw cap 101' is screwed home, the two blocks will be held firmly seated against the interior shoulder 103, so that a tight seal can be made by a washer inserted between the flange of the cap 101' and the block 105.

Thus, by providing casing 100-101' in two parts and mounting the interior components 106, 105 within the casing, manufacturing costs can be reduced to a minimum. In addition it enables the sealing of the piston chamber C to be closed by an independent plug 110 with constant fluid tightness of the chamber C and no longer is the fluid tightness of the apparatus as a whole dependent on the accurate machining of the parts of the outer casing. Moreover the interior parts can be replaced or renovated when worn.

As shown in Figure 1, the seat 40' for the outlet valve V is provided by a separate valve block 105, which enables the seat to be ground independently of the casing so that in the event of wear, the block can be removed for grinding. In order to provide for replacement or renewal of the valve V which due to the high speed of operation of the gun is subjected to considerable wear and tear, the piston rod 112 is tapered at its end as at 113 and the valve V, backed by a reinforcing member 113', is formed with a corresponding taper so that it remains firmly in place under the action of the piston and can readily be replaced. This construction also reduces the possibility of shearing which is liable to take place when the valve is attached to the piston rod by screwing, because immediately the screw works loose the valve will chatter and break. The inlet valve D, as shown in Figure 1 is preferably formed in the limb 107' of the spider block 106, which limb is of slightly increased thickness to accommodate a drilling 120 provided at one end of a tapered seat 121 for a steel ball comprising the valve D and which is urged against its seat by a spring 122 held in position by a screw plug 123.

The valve control rod 16 is mounted in a pack-

ing gland 16' so that an end pressure on the rod hand knob M will unseat the valve D to admit fluid pressure from the interior chamber B past the valve D, whence it flows through a duct 116 into the interior chamber C to cause a displacement of the piston P against the spring S thus unseating the valve V to effect a release of the air pressure within the chamber B. Following the release of pressure, valve V will be moved to its closed position under the action of spring S cutting off the blast. As soon as the pressure in chamber B has built up the same operation will take place which gives rise to a rapid succession of air or steam or other fluid pressure blasts.

It will be appreciated that the spider construction of the block 106 permits of a direct through flow of the pressure fluid from the inlet 102 past the sector shaped openings between the legs 107-107' and outwardly through the discharge orifice O without any reversal in direction thereby reducing friction and improving the efficiency of the gun as a whole. Moreover, the construction of the block 106 enables it to be die-cast giving a cheaper manufacture than where a number of holes have to be drilled through an interior block.

I claim:

1. A fluid pressure actuated gun comprising a casing having an interior pressure chamber and being provided at one end with an opening for admitting fluid under pressure to said chamber, a closure member connected to the opposite end of said casing, a cylinder block within said chamber, a valve block, seating means within said casing for mounting said blocks in said casing one against the other and said other against said seating means, said one block being engaged by said closure member to be held in position thereby, said valve block and said closure member having a discharge opening, the valve block being provided with a valve seat at the discharge opening, a discharge valve engageable against such seat and biased to closed position, said cylinder block having a passage to permit the flow of fluid through said casing from said inlet opening to said discharge opening, said cylinder block having a cylinder therein, a piston reciprocable in said cylinder and connected to said discharge valve, and means for controlling the admission of pressure fluid from said chamber to said cylinder to move said piston and open said discharge valve.
2. The combination claimed in claim 1 wherein in said cylinder block is constructed in the form of a spider having arms machined to fit within said casing and to provide said passage for the direct passage of pressure fluid from the inlet opening to the discharge end of said casing.
3. The combination claimed in claim 2 in which one of the arms of said spider is formed with a duct providing access from said pressure chamber to said cylinder, and a control valve in said duct for controlling the admission of air from said pressure chamber to said cylinder, said duct and said control valve constituting said means for controlling the admission of pressure fluid from said chamber to said cylinder.
4. A fluid pressure actuated blast gun comprising a casing having an interior pressure chamber, said casing having an inlet opening at one end for admitting fluid under pressure to said chamber, a closure member for the opposite end of said casing, a cylinder block and a valve block in said casing, said casing having a coun-

terboré providing a shoulder for fixing said blocks in said casing one against the other and said other against said shoulder, said closure member engaging said one block to fix said blocks in said casing, said valve block and said closure member having a discharge opening, the valve block being provided with a valve seat at the discharge opening, a discharge valve biased for movement towards said seat, said cylinder block having passages for the flow of pressure fluid from said inlet opening to said discharge valve, said cylinder block having a cylinder, and a piston in said cylinder connected to said discharge valve and operable under pressure in said chamber to open said discharge valve.

5. The combination claimed in claim 4 in which said cylinder block is located in said chamber at the end thereof adjacent said closure member, a screw plug closing the end of said cylinder remote from said closure member, and

10

15

20

a spring in said cylinder having its ends respectively engaging said piston and said screw plug.

6. The combination claimed in claim 5 provided with a piston rod connecting said piston to said discharge valve, said piston rod having a tapered end for mounting said discharge valve.

JOHN EDWARD CROSSLEY NESHAM.
